UNITED STATES PATENT OFFICE

121,677

DESIGN FOR A HOT WATER TANK

Roy C. Ingersoll, Winnetka, Ill.

Application April 28, 1939, Serial No. 84,645

Term of patent 14 years

To whom it may concern:

Be it known that I, Roy C. Ingersoll, a citizen of the United States, residing at Winnetka, in the county of Cook and State of Illinois, have invented a new, original, and ornamental Design for a Hot Water Tank, of which the following is a specification, reference being had to the accompanying drawing, forming a part thereof, wherein:

Fig. 1 is a front elevational view of a hot water tank showing my new design;

Fig. 2 is a top plan view thereof on an enlarged scale; and

Fig. 3 is a fragmentary front elevational view thereof on a still greater enlarged scale with a portion of the tank broken away for convenience of illustration.

The dominant features of my design reside in the portions shown in full lines.

I claim:

The ornamental design for a hot water tank, as shown and described.

ROY C. INGERSOLL.
